Patented Dec. 20, 1921.

INVENTOR

Stuart B. Brodie
by *Wm. M. Brady*

UNITED STATES PATENT OFFICE.

STUART B. BRODIE, OF WILMERDING, PENNSYLVANIA.

COMBINED OIL AND GAS BURNER.

1,400,657.

Specification of Letters Patent. Patented Dec. 20, 1921.

Application filed June 6, 1918. Serial No. 238,571.

To all whom it may concern:

Be it known that I, STUART B. BRODIE, a citizen of the United States, residing at Wilmerding, in the county of Allegheny and 5 State of Pennsylvania, have invented new and useful Improvements in Combined Oil and Gas Burners, of which the following is a specification.

This invention relates to combined oil and 10 gas burners, whereby either oil or gas may be employed as fuel, or both together.

The principal object of my invention is to provide an improved burner adapted to produce an intense heating flame.

15 In the accompanying drawing, the single figure is a sectional view of a combined oil and gas burner embodying my improvements.

As shown in the drawing, the construction 20 may comprise a body casting 1, having an air chamber 2, communicating with an air inlet 3. An air adjusting cap 4, having a central opening 5, is screwed onto the body 1, and a gas inlet member 6, is screwed into 25 the body 1, at the side opposite to the air cap 4.

A threaded section of pipe 7 is screwed into the member 6, and on the outer end of the pipe is screwed a gas nozzle 8, which 30 when in position is adjacent to the opening 5. Within the pipe 7 is mounted an oil spindle 9, having screw threaded engagement with the member 6, and having an oil conduit 10, and an oil nozzle 11, screwed into 35 the outer end.

An oil regulating valve 12 is applied to the rear end of the oil spindle 9, and nuts 13, are provided for holding the oil spindle 9 in its adjusted position.

40 It has been found that in order to secure an intense heating flame, it is necessary to provide ample area for the flow of gas and this is accomplished by constructing the gas nozzle 8 with an annular outlet area 14, substantially equal to the area of the annular 45 gas chamber 15.

The outer end of the nozzle 8 is also provided with an inwardly extending annular lip 17, for directing the flow of gas toward 50 the center of the opening 5, as this has the effect of properly combining the gas and air, so to produce an intimate mixture and a high burning efficiency.

55 The oil nozzle 11 should be positioned, so as to provide the proper gas outlet through the surrounding gas chamber, and for this

purpose the oil spindle with its nozzle can be accurately adjusted by simply turning the oil spindle after loosening the nuts 13. When the proper adjustment has been made, 60 the nuts 13 are again tightened.

In operation, if gas alone is to be employed as fuel, the oil valve 12 is closed and gas flows through the inlet 16 to the gas chamber 15, and thence through the outlet 65 area 14 to the opening 5, where the gas is combined with air flowing from the air chamber 2, around the gas nozzle 8 to the opening 5.

If oil alone is used as fuel, the oil valve 70 12 is opened, and then oil is supplied through the oil conduit 10 and the oil nozzle 11, and a combustible mixture is then formed with the air, at the opening 5.

It will be evident that both oil and gas can 75 be used together as fuel by permitting the flow of oil as well as gas.

Having now described my invention, what I claim as new and desire to secure by Letters Patent, is:—

1. A gas burner comprising a body member having an air chamber, a cap member 80 having a discharge outlet opening communicating with said chamber, and a gas nozzle mounted in said air chamber and having an annular gas outlet, the adjacent faces of the cap member and the gas nozzle being interconverging frustums of cones converging toward the longitudinal axis of the gas nozzle to form an annular air outlet, a sharp 85 edge separating the annular air and gas outlets so that the air and gas outlets are in close proximity to each other and to the outlet opening in said cap member.

2. A combined oil and gas burner comprising 90 a body member having an air chamber, a gas nozzle mounted in said air chamber and having an annular gas outlet, and an oil spindle having an oil nozzle mounted in said gas nozzle, the adjacent faces of the cap 100 member and the gas nozzle being interconverging frustums of cones converging toward the longitudinal axis of the gas nozzle to form an annular air outlet, the gas nozzle having an annular lip for directing the flow 105 of gas through the gas outlet toward the longitudinal axis of the burner and the air, oil, and gas outlets being in close proximity to the outlet opening in the cap member.

In testimony whereof I have hereunto set 110 my hand.

STUART B. BRODIE.
